EDWARD V. TRELEVEN, OF LOS ANGELES, CALIFORNIA, ASSIGNOR TO PEERLESS PRODUCTS COMPANY, A CORPORATION OF CALIFORNIA

WAX DISTRIBUTING MEANS

Application filed February 1, 1926, Serial No. 85,251. Renewed July 23, 1929.

My present invention relates particularly to novel wax-distributing means; and, although I may employ a waxing and polishing organization identical with or similar to one 5 or another of the types described in, for example, the application of Edna R. Gedge, Serial No. 82735, filed January 21, 1926, it is an especial object of this invention to provide novel and inexpensive wax cartridges 10 comprising shells formed of paper, or of another fibrous material, adapted to form a tight closure when pressed against a metallic surface; and, in preferred embodiments of my invention, these shells may be suitable for use both in the distributing of wax, 15 through the usual channels of wholesale and retail trade, and also suitable for use in the final distribution or application of wax, in which a plunger may be used in forcing the 20 contents of my wax cartridges through a channel or channels therebelow, and toward and through the main body of a waxer, comprising parts adapted to cooperate therewith.

It is an object of this invention to provide 25 inexpensive wax cartridges comprising shells sealed against deterioration and sufficiently rigid to withstand ordinary usage, the material of said shells being adapted to yield very slightly under longitudinal pressure, to obviate the need of a gasket therebelow, in preventing a lateral escape of wax when a plunger is used to force the same out through pivotally connected members and through the main body of a waxer; and my invention includes methods of preparing and using the 35 mentioned cartridge as well as preferred features of cartridge construction, and preferred cooperative features of waxer construction, as hereinafter described.

40 Other objects of my invention, including the use of spirally wound strips in the formation of my cartridge shell, and the use of preferred coating materials in so treating the same as to prevent escape of contents of 45 my cartridges, and including an optional flaring of what I may term the plunger-receiving end of some or all of my cartridges, may be best appreciated from the following description of alternative embodiments of my 50 invention, taken in connection with the ap-

pended claims and the accompanying drawing, in which

Fig. 1 is a vertical section through a waxer and a cartridge illustrating my invention, this form involving the use of a longitudinally split chamber comprising a part permanently secured by a pivot pin, near its lower end; and comprising also a locking ring. 55

Fig. 2 is a fragmentary view illustrating an alternative method of connecting a relatively movable chamber section. 60

Fig. 3 is a detail view, corresponding to the upper portion of Fig. 1, but with a plunger omitted, this figure illustrating an alternative form of cartridge and cooperating features 65 of wax chamber construction.

Fig. 4 is an elevational view, with parts broken away, of a cartridge of the general type illustrated in Fig. 1.

Fig. 5 is a view corresponding to the upper 70 portion of Fig. 4, but showing cartridges of the general type illustrated also in Fig. 3 as closed by a plug.

Referring to the details of that specific embodiment of my invention illustrated in Figs. 1 and 4, 11 j is the main body or weight of a waxer, this body being pivotally connected with a wax or cartridge chamber comprising a major section 12 j and a relatively movable section 12' j ; these sections together constituting a cylindrical member and being integral with a correspondingly divided cap, interiorly threaded to receive corresponding threads provided upon a handle 13 j , or upon a metallic thimble or extension coaxial with a handle 80 by which the entire waxer is manipulable. 85

The lower end of the mentioned handle or thimble is shown as provided with a cylindrical enlargement or plunger 14 j , the descent of which is effective to force the wax downward 90 through and out from a suitable cartridge, such as a cartridge comprising a cylindrical shell 15 j ; and, to facilitate the insertion of fresh cartridges, and the removal of empty shells, I may secure the movable cartridge 95 chamber section 12' j either by means such as a pivot pin 16 j , extending through cooperating lugs 17 j on said movable section, and corresponding lugs 18 j on the major section 12 j , or I may employ, as suggested in Fig. 2, a lug 100

in the form of a mere hook $17j$, adapted to engage a rounded transverse member $16k$ in such manner as to permit the removable section to be entirely separated from associated parts.

Using either of the constructions just described, it will be obvious that, upon the insertion of a suitable cartridge $28j$, substantially as shown, a tapered ring $19j$ being momentarily lifted, the movable section $12j'$ is swung upward into parallelism with the major section $12j$, and said ring is then dropped or forced downward sufficiently that all parts will be locked in their intended relationships; and the subsequent rotation of the handle or thimble $13j$ may then be relied on to force wax from the mentioned cartridge, or its equivalent, out through wax delivery and outlet passages such as are indicated at $23j$ and $24j$, to enable the same to be used in the waxing of a floor, or the like, in a known manner.

It will be appreciated that the advance of the plunger $14j$, or its equivalent, is due to an engagement between external threads $20j$ with corresponding internal threads provided at $21j'$ and $21j''$ upon the respective cap sections integral with the chamber sections $12j$ and $12j'$; and it is an important feature of my present invention that, by forming the described cartridges of paper, such as has heretofore been used in the construction of mailing tubes, and the like, or of an equivalent fibrous material capable of yielding sufficiently to form a tight closure, in the line of contact of its lower edge $22j$ with a substantially flat circular area provided, at $25j$, in the bottom of the described wax container, or in the bottom of a wax container of any preferred alternative construction, I obviate all need of a gasket, or the like, to prevent lateral escape of wax, substantially the entire contents of each cartridge being forced, upon the depression of the plunger $14j$, or its equivalent, which should fit snugly therein, out through the described passages $23j$ and $24j$, extending respectively through a laterally offset neck and through an upstanding projection on the waxer body,—the latter elements being pivotally connected, as in the mentioned application of Edna R. Gedge, or otherwise, as may be desired.

Although the wax cartridges $28j$ may be cylindrical throughout their entire length, and although they may be closed in any preferred manner and/or coated or saturated with any preferred suitable material, I find it highly advantageous not only to employ paper tubes formed of suitable strips spirally wound, in order to avoid any use of longitudinal seams, but to saturate or coat the same with a material, such as a solution of sodium silicate (as ordinarily obtainable at drug stores, under the name of water glass) this being applied either with the aid of a

brush, or by dipping. For example, having provided tube sections of suitable length, I may moisten the interior and exterior surfaces thereof with sodium silicate, then applying cupped paper or other plugs or caps $26j$, preferably treated with the same solution, to the lower ends of a row of the treated tubes (the caps being preferably applied while the coating thereon and/or the coating on the tubes is still fluent); I may then fill the tubes with the desired wax (hot or cold—the composition of floor wax being well known and constituting no part of my invention) thereafter closing the upper or plunger-receiving ends of the tubes, as by applying thereto caps $27j$, preferably also treated in the general manner above described. Instead of, or in addition to applying the respective caps while the coating materials thereon, or on the shells $15j$, are still fluent, I may dip the respective ends, or entire cartridges, after one or both of the mentioned caps, or equivalent closure elements, are applied.

I suggest, in Fig. 3 (in which no plunger is shown, this element being preferably of the same general character as that illustrated in Fig. 1) a cartridge $28m$ which is slightly flared at the upper end $29m$ thereof, in a manner favorable to the guidance of a plunger thereto; and I show the walls of the respective wax chamber sections $12m$ and $12m'$ as provided with corresponding angular concavities $29m'$, providing space for the mentioned flaring of the cooperating cartridge. I also suggest, in Fig. 5, the use at the upper end of each cartridge $28m$ of a tapered plug $30m$, adapted to interfit within the correspondingly tapered upper portion of the shell $15m$ and tending to prevent deformation thereof, during shipment and/or storage. It will be obvious that, if desired, the plugs $30m$ or their equivalents, whether formed of wood, or of any preferred material, may be coated or saturated in the described manner; and the dimensions of the wax chamber into which the described cartridges are to be inserted may be such as to necessitate the removal of the described caps, and/or plugs, before the same are inserted, for use as described.

Although I have herein described alternative embodiments of my invention, it should be understood not only that various features thereof may be independently used, but also that numerous modifications might be made, by those skilled in the art to which this case relates, without the slightest departure from the spirit and scope of this invention, as the same is indicated above and in the following claims.

I claim as my invention:

1. In wax distributing means: a waxer comprising a weight, provided with an out-

let passage for wax; a sectional wax chamber member; pivot means connecting said chamber member with said weight, having an intercommunicating wax passage there-
5 through; a handle extending from said wax chamber for the operation of said weight; a plunger mounted on the end of said handle movable within said chamber; and means comprising a freely slideable annular ring,
10 movable longitudinally of said handle for locking sections of said wax chamber in closed position.

2. In wax distributing means: a waxer comprising a weight, provided with an outlet
15 passage for wax; a sectional wax chamber member; pivot means connecting said chamber member with said weight, having an intercommunicating wax passage there-
through; a handle extending from said
20 weight; a plunger mounted on the end of said handle movable within said chamber; and means comprising a freely slideable annular ring, movable longitudinally of said handle for locking sections of said wax chamber
25 in closed position, said sections comprising a fixed section and a hinged section pivoted at one end of said fixed section.

3. In a wax distributing means; a waxer head having a wax delivery passage; a wax
30 container pivoted to the head; and a handle for manipulating the head and axially movable of the container for expressing wax therefrom into the head; said container including a pair of longitudinal sections piv-
35 otally joined together adjacent that part of the container that is nearest the head.

4. In a wax distributing means; a waxer head having a wax delivery passage; a wax
40 container pivoted to the head; a handle for manipulating the head and axially movable of the container for expressing wax therefrom into the head; said container including a pair of longitudinal sections piv-
45 otally joined together adjacent that part of the container that is nearest the head; and means longitudinally movable with respect to the container, for holding the sections together.

5. In a wax distributing means; a waxer head having a wax delivery passage; a wax
50 container pivoted to the head; and a handle for manipulating the head and axially movable of the container for expressing wax therefrom into the head; said container including a pair of longitudinal sections piv-
55 otally joined together on an axis adjacent the end of the container and transversely thereof.

In testimony whereof, I have hereunto set
my hand at Los Angeles, California, this
60 26th day of January 1926.

EDWARD V. TRELEVEN.
